UNITED STATES PATENT OFFICE

95,919

DESIGN FOR AN AIRCRAFT CHAIR

Lewis C. McCarty, Jr., Towson, and Drew M. Helwig, Baltimore, Md., assignors to The Glenn L. Martin Company, Baltimore, Md.

Application August 18, 1934, Serial No. 52,988

Term of patent 7 years

To whom it may concern:

Be it known that we, Lewis C. McCarty, Jr., and Drew M. Helwig, citizens of the United States, and residents, respectively, of Towson, in the county of Baltimore and State of Maryland, and of Baltimore, in the State of Maryland, have invented a new, original, and ornamental Design for an Aircraft Chair, of which the following is a specification, reference being had to the accompanying drawings, forming part hereof.

Fig. 1 is a front perspective view of the subject chair, showing portions of the ornamentally

braced structure, a safety belt, a sectionally upholstered sling-seat and back.

Fig. 2 is a back perspective view of the subject chair showing portions of the ornamentally braced structure, the safety belt, and the slip-over portion of the upholstered sling-back shown in Figure 1.

We claim:

The ornamental design for an aircraft chair substantially as shown and described.

LEWIS C. McCARTY, JR.
DREW M. HELWIG.
